(57) **CLAIM**

The ornamental design for a car dashboard, substantially as shown and described.

DESCRIPTION

FIG. 1 is a perspective view of a car dashboard in accordance with the present design;

FIG. 2 is a front view of the car dashboard;

FIG. 3 is a top plan view of the car dashboard;

FIG. 4 is a right side view of the car dashboard; and,

FIG. 5 is a left side view of the car dashboard.

The structural features depicted by means of broken lines in the drawing figures have been shown for the purposes of illustrating environmental structure only and form no part of the claimed design.
